L. J. BERKELEY.

RAIL ANCHOR.

APPLICATION FILED SEPT 14, 1920.

1,379,383.

Patented May 24, 1921.

UNITED STATES PATENT OFFICE.

LAURENCE J. BERKELEY, OF MILWAUKEE, WISCONSIN, ASSIGNOR TO THE P. & M. COMPANY, OF CHICAGO, ILLINOIS, A CORPORATION OF ILLINOIS.

RAIL-ANCHOR.

1,379,383.

Specification of Letters Patent. Patented May 24, 1921.

Application filed September 14, 1920. Serial No. 410,287.

To all whom it may concern:

Be it known that I, LAURENCE J. BERKELEY, a citizen of the United States, residing at Milwaukee, in the county of Milwaukee and State of Wisconsin, have invented certain new and useful Improvements in Rail-Anchors, of which the following is a specification.

My invention relates to devices for resisting the longitudinal creeping movement of railroad rails, such devices being generally known as rail anchors, anti-creepers, or rail stays.

The primary object of the invention is to provide an improved device of this character which when applied to its operative position will take a firm shackle hold on the base flange of a rail, preferably on the upper and lower surfaces of the base flange, and maintain such hold by a combined spring action, and wedging engagement of the parts of the anchor device, and increase its grip on the rail base when the rail moves longitudinally.

The invention contemplates as a further and more specific object to provide an improved rail anchor consisting of two parts which are so connected together that they, in effect, constitute a one-piece rail anchor that may be readily applied to rail bases of different widths.

The invention consists in the novel arrangements and constructions of parts hereinafter described and claimed for carrying out the above stated objects, and such other incidental objects as will appear from the following description of the embodiment illustrated in the accompanying drawing, wherein—

Figure 1 is an end view, partly in section, of a rail anchor constructed in accordance with my invention, showing the parts of the device in the position which they assume before they are moved to their rail gripping position;

Fig. 2 is a view similar to Fig. 1, showing the parts of the anchor device moved to their rail gripping position;

Fig. 3 is a front view in elevation of the structure shown in Fig. 2; and

Fig. 4 is a detail view in perspective of the anchor device shown in the preceding figures.

Like characters of reference designate like

parts throughout the several figures of the drawing.

The invention in its preferred embodiment contemplates an anchor device adapted to grip one edge of the base flange of a rail with a firm shackle hold, and to maintain said grip by means of a locking member which hooks over the opposite edge of the rail base.

In the drawing the device is shown as consisting of an inverted U-shaped shoe member 10, of spring metal, the legs 11, 12 of which are provided with notches 13, 14, which fit over one edge of the base flange of the rail 15 at different points. The leg 12 of the shoe extends below the rail base to provide a foot 16 which bears against one of the vertical faces of a cross-tie 17. The edges 18, 19 and 20, 21 of the notches 13, 14 are forced into a firm shackle, biting engagement with the upper and lower surfaces of the rail base by spreading the extremities of the shoe member from the position shown in Fig. 1, to the rail gripping position shown in Fig. 2. In order to insure the proper flexing of the shoe member, the top portion of the shoe is reduced in thickness, as indicated at 22, so that it will readily flex at this point, thereby permitting the legs 11, 12 to assume the desired angular position to insure a firm gripping contact of the notches 13, 14 on the rail base.

The extremities of the shoe are preferably spread apart by means of a bar 23 extending transversely under the rail base. This bar is hinged adjacent one end to the lower edge of the leg 11 of the shoe, and is provided at the other end with a hook portion 24 which projects over the opposite edge of the base flange of the rail when the anchor is in its applied position. The hinged connection between the shoe 10 and transverse bar 23 may be of any suitable construction, though preferably consists of an upturned lip 25 on the leg 11 which extends through an elongated opening 26 in the bar 23. When applying the device to a rail, the slots of the shoe 10 are fitted over one edge of the base flange of a rail with the tie abutting foot 16 adjacent a cross-tie, as shown in Fig. 1. The hinged bar 23 is then raised from its inoperative position, shown in Fig. 1, to a substantially horizontal position, as shown in Fig. 2. The width of the bar is greater than the

normal distance between the legs 11, 12 of the shoe, and when raised as above mentioned, assumes a wedging position between the legs, so as to spread them apart to the 5 angular position shown in Fig. 2. When raising the bar 23 to its normal wedging position the tapered lip 27 of the hook 24 being forced over the edge 28 of the rail base, will flex the hook portion to the dotted line 10 position shown in Fig. 3, until the lip 27 clears the upper edge of the base flange, whereupon the lip will snap over the upper edge of the flange and support the bar in an angular position slightly below its pivot center. The curved surface 29 of the tie abutting foot and the tendency which the spring legs 11, 12 have to return to the position 15 from which they were sprung will prevent the bar 23 from swinging to a position above 20 its pivot center. With this construction, pressure applied to the tie abutting foot 16, by reason of a creeping movement of the rail, is transmitted through the bar 23 to the lower extremity of the leg 11 of the shoe, 25 thereby increasing the grip of the edges 18, 19 of notch 13 on the upper and lower surfaces of the rail. The hook end of the bar, being in engagement with the opposite edge of the rail base, prevents any lateral 30 placement of the shoe tending to loosen its effective grip on the rail.

While I have described my invention in one specific embodiment, it will be obvious that modifications in structure might be 35 made without departing from the principles of my invention. I therefore do not wish to limit myself to the specific structure shown and described except as specifically limited in the appended claims.

40 I claim:

1. A rail anchor comprising a rail base engaging member provided with recesses which fit over one edge of a rail base and formed with a tie-abutting portion; said 45 member being adapted to be strained in its application to a rail to bring said recesses into gripping contact with the rail base.

2. A rail anchor comprising a rail base engaging member provided with recesses which fit over one edge of a rail base and formed with a tie-abutting portion; said member being made of spring metal and adapted to be strained in its application to a rail to bring said recesses into gripping 55 contact with the rail base.

3. A rail anchor comprising a rail base engaging member provided with portions formed with recesses which fit over one edge of a rail base, and formed with a tie-abutting portion; said member being adapted to be strained in its application to a rail to spread said recessed portions apart and bring said recesses into gripping contact 60 with the rail base.

4. A rail anchor comprising a rail base 65 engaging member provided with recesses which fit over one edge of a rail base and formed with a tie-abutting portion; said member being adapted to be strained in its application to a rail to bring said recesses 70 into gripping contact with the upper and lower surfaces of the rail base.

5. A rail anchor comprising a rail base engaging member having vertically disposed legs provided with recesses which fit over 75 one edge of a rail base, and formed with a tie abutting portion; said member being made of spring metal and adapted to be strained in its application to a rail to bring said recesses into gripping contact with the 80 rail base.

6. A rail anchor comprising a rail base engaging member having vertically disposed legs provided with recesses which fit over one edge of a rail base at different points 85 and formed with a tie abutting portion; said legs being adapted to be strained in application of the device to the rail to effect a shackle grip of said recesses on the upper and lower surfaces of said rail. 90

7. A rail anchor comprising a rail base engaging member having vertically disposed legs provided with recesses which fit over one edge of a rail base at different points and formed with a tie abutting portion; 95 said legs being adapted to be spread apart to an angular position in application of the device to a rail to effect a shackle grip of said recesses on the upper and lower surfaces of the rail base. 100

8. A rail anchor comprising a spring metal rail-gripping member having recesses to fit over one edge of a rail base and provided with a tie abutment, and a wedging member adapted when in its operative position to strain said rail gripping member to bring said recesses into gripping contact with the rail base. 105

9. A rail anchor comprising a spring metal rail-gripping member having recesses 110 to fit over one edge of a rail base and provided with a tie abutment, and a wedging member provided with a jaw to engage the opposite edge of the rail base and adapted, when in its operative position, to strain said 115 rail gripping member to bring said recesses into gripping contact with the rail base.

10. A rail anchor comprising a spring jaw member having vertically disposed legs provided with recesses to fit over one edge of a rail base, and a wedge member having a hinged relation with said spring jaw adapted to be moved to force said recesses into gripping contact with the rail base. 120

11. A rail anchor comprising a spring jaw 125 member having vertically disposed legs provided with recesses to fit over one edge of a rail base, and a hinged member adapted

to be moved into a wedging position between said legs to force said recesses into gripping contact with the rail base.

12. A rail anchor comprising a spring jaw member having vertically disposed legs provided with recesses to fit over one edge of a rail base, and a hinged member adapted to be moved into wedging position between said legs to force said recesses into gripping contact with the rail, and provided with a jaw adapted to engage the opposite edge of said base to maintain said hinged member in its wedging position.

13. A rail anchor comprising a spring jaw member having substantially vertically disposed legs formed with recesses adapted to fit over one edge of a rail base, and a bar extending transversely of the rail, hinged to said jaw member, and provided with a jaw adapted to fit over the opposite edge of said rail base, said bar being adapted to be raised to tension said legs and to force said recesses into gripping contact with the upper and lower surfaces of the rail base.

14. A rail anchor comprising a spring jaw member having substantially vertically disposed legs formed with recesses adapted to fit over one edge of a rail base, and a bar extending transversely of the rail base adapted to be moved into wedging position between said legs to force them apart and bring said recesses into gripping contact with the upper and lower surfaces of the rail base; said bar being hinged adjacent one end to said spring jaw and formed at the other end with a spring hook adapted to snap over the opposite edge of said base when the bar is moved to its wedging position.

15. A rail anchor comprising a spring jaw member having substantially vertically disposed legs formed with recesses adapted to fit over one edge of a rail base, one of said

legs provided with a tie-abutting foot, and a hinged member adapted to be wedged between said legs whereby said legs are strained during the presence of a creeping pressure to increase the grip of the device on the rail.

16. A rail anchor comprising a spring jaw member having substantially vertically disposed legs formed with recesses adapted to fit over one edge of a rail base, one of said legs providing a tie abutting foot, and a hinged member adapted to be wedged between said legs below said recesses whereby said legs are strained during the presence of a creeping pressure to increase the grip of the device on the rail.

17. A rail anchor comprising a spring jaw member having substantially vertically disposed legs formed with recesses adapted to fit over one edge of a rail base, one of said legs providing a tie abutting foot, and a hinged member adapted to be wedged between said legs below said recesses whereby said legs are strained during the presence of a creeping pressure to increase the grip of the device on the rail; said hinged member being provided with a jaw adapted to engage the opposite edge of the rail base to lock said bar in its wedging position.

18. A rail anchor comprising a substantially U-shaped spring jaw member having rail gripping recesses, and reduced in thickness at one point to increase its flexibility, and means for spreading the extremities of said member to an angular position so as to effect a gripping contact of said recesses on the rail; said spreading means being disposed in a position to impart pressure to one of said extremities during a creeping movement of the rail to increase the grip of the device on the rail base.

LAURENCE J. BERKELEY.
